UNITED STATES PATENT OFFICE.

OTTO KRAUS, OF NEW YORK, N. Y.

SEAT-POST AND HANDLE-BAR FASTENER.

SPECIFICATION forming part of Letters Patent No. 595,179, dated December 7, 1897.

Application filed July 11, 1896. Serial No. 598,853. (No model.)

To all whom it may concern:

Be it known that I, OTTO KRAUS, a citizen of the United States of America, and a resident of New York, in the county and State of 5 New York, have invented certain new and useful Improvements in Seat-Posts and Handle-Bar Fasteners, of which the following is a specification.

My invention has reference to improvements in fastenings for saddle-posts for bicycles and other velocipedes, and has for its object to provide means whereby the saddle-post or other support is securely held, while its height can be readily adjusted.

With this object in view my invention consists, essentially, in the combination, with a tubular member, of a post movably fitting into said member and a wedging-piece extending through the member and the post and adapted to engage with the post to lock the same.

The nature of my invention will best be understood when described in connection with the accompanying drawings, in which—

Figure 1 represents an elevation of a portion of a velocipede provided with my improved fastening device as adapted for the saddle-post. Fig. 2 is a bottom view of the same. Fig. 3 is a perspective view of the wedging-piece.

Similar letters and numerals of reference designate corresponding parts throughout the several views of the drawings.

Referring to the drawings, the letter A designates the diagonal tubular member of a diamond frame of the usual construction. Into said member is fitted the post B of the saddle-support C, said post being tubular, as usual.

In carrying out my invention I provide the post B with a longitudinal slot 1 and the tubular member A with an opening or passage 2 near its upper end, placed in the line of the slot 1.

D is the wedging-piece, composed of a tongue 3, lying within the post B, and a part 4, bent substantially at right angles thereto and forming a handle for said wedging-piece. In the present example I have made the said wedging-piece substantially elliptical in shape, with the major axis somewhat greater than the internal diameter of the post B, while the minor axis is substantially equal in

length to the said diameter of the post B. The wedging-piece can be inserted into the tubular member A by slipping the same, with 55 the elliptical portion foremost, down into the tube A and then passing the handle 4 upwardly through the passage 2 in the member A, or by making the slot and passage wide enough to turn the wedging-piece the latter 60 can be inserted directly. The wedging-piece, it will be noticed, can turn in the member A as an axis. A spring 5 may be attached to the inner portion of the wedging-piece, which spring holds the same upwardly, substantially 65 as shown in Fig. 1, and offers resistance to displacement, thereby preventing overbalancing when the saddle-post is removed.

It is now evident that when the saddle-post is inserted into the member A, while the wedging-piece is held in an oblique position with respect to the diameter of the tube by pressing on the handle 4, the saddle-post B can be slipped into the member A a distance 70 to correspond to the required height of the saddle. When, however, the handle 4 is released and the rider mounts the saddle, the wedging-piece D immediately grips the saddle-post and tends to expand the same, and 75 as it cannot follow the motion of the post it retains the same positively in the position to which it had been adjusted. In the present instance I have shown the usual reinforcement E at the juncture of the several tubes, 80 which reinforcement is perforated at 6 for the passage of the wedging-piece.

It is of course to be understood that the fastening device may equally well be applied to handle-bars and other supports and that 85 any optional shape could be given to the same so long as its length exceeds that of the interior diameter of the tubular post.

It will be readily understood that by the above-described fastener the saddle or handle-bar is always held in line with the frame, 90 while at the same time its height can be very quickly adjusted.

What I claim as new is—

1. A support for saddle and like posts, comprising a tubular post, a tubular member receiving said post, and a wedging-piece placed within the said post and provided with an arm or handle extending exterior to the tu-

bular member; said piece being of greater length than the distance across the corresponding portion of the post and supported by the tubular member, substantially as described.

2. A support for saddle and like posts, comprising a tubular post, a tubular member receiving said post, a wedging-piece placed within the said post and provided with an arm or handle extending exterior to the tubular member; said piece being of greater length than the distance across the corresponding portion of the post and supported by the tubular member, and a spring acting on the wedging-piece for pressing the same upwardly, substantially as described.

3. A support for saddle and like posts, com-

prising a tubular, slotted post, a tubular member receiving said post and provided with a passage or opening, and a wedging-piece composed of an inner tongue of greater length than the diameter of the tubular post and a handle extending through said slot and passage, substantially as and for the purpose specified.

In testimony that I claim the foregoing as my invention I have signed my name, in presence of two witnesses, this 1st day of July, 1896.

OTTO KRAUS.
